Donald M. Aubrey, Union, Ill., assignor to Aubrey Manufacturing, Inc., Union, Ill., a corporation of Delaware

Filed Apr. 30, 1962, Ser. No. 69,884

Term of patent 14 years

(Cl. D81—25)

FIGURE 1 is a perspective view of the combination wall-type warming oven and cabinet embodying my ornamental design, the bottom and rear being substantially flat and plain.

FIGURES 2 and 3 are face and end views, respectively.

The dominant features of my design reside in the portions shown in full lines.

I claim:

The ornamental design for a combination wall-type warming oven and cabinet, substantially as shown and described.
